Arthur Bates
By his Attorney
Robert M. Howard

UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

CUTTING MACHINE.

Application filed April 30, 1919. Serial No. 293,615.

To all whom it may concern:

Be it known that I, ARTHUR BATES, a subject of Great Britain, residing at Leicester, Leicestershire, England, have invented certain Improvements in Cutting Machines, of which the following description, in connection with the accompanying drawings, is a specification, like reference characters on the drawings indicating like parts in the several figures.

This invention relates to cutting machines and more particularly to cutting machines designed to cut sheet material by the use of freely movable dies.

The invention is disclosed in connection with a machine of the type shown in Patent No. 921,503, granted May 11, 1909, to Arthur Bates. As usually constructed this machine comprises a support or cutting bed for the stock, a freely movable die designed to be selectively positioned upon the stock on the cutting bed, and a presser member so mounted that it may be oscillated to bring it into operative position over the die and depressed to effect a pressure applying operation on the die. It is an object of the invention to provide an improved machine of the class described which will operate in such manner as to insure clean cutting of the stock under all conditions and especially when operating upon particularly heavy material or upon fabrics in a multiplicity of layers. The invention is applicable also to machines which embody wooden cutting blocks, wherein the cutting of sheet fabric or leather even when relatively light sometimes presents difficulties due to unevenness or inequalities in the cutting surface of the block or cutting bed.

In one aspect the invention consists in the provision of means for effecting a plurality of pressure applying operations upon a die to cause the die to cut completely through the stock upon a single actuation of the starting or controlling means of the machine. Preferably the means just described will be so constructed as to cause a pressure applying operation and a movement of separation of the presser members of less extent than the movement of applying pressure, and then an automatic re-application of pressure in the same cycle of operations of the machine. One advantage of such a construction resides in the fact that, owing to the relatively slight movement of separation

of the presser members before the re-application of the pressure, there is practically no possibility of lateral displacement of the movable presser member with respect to the die during the cycle of operations.

In another aspect the invention consists in the provision of a toggle mechanism acting on a presser member for forcing a die through material on a cutting bed, for causing the relief of the pressure on the die and the re-application of pressure on the die to ensure clean cutting of the stock, all in the same cycle of operations of the machine. In a practical form of the invention the toggle mechanism is constructed to move to straightened position to cause the application of pressure on the die, then to move beyond center to effect a movement of separation of the presser members, and finally to return to center or to straightened position to produce a re-application of pressure upon the die. Preferably the toggle mechanism will be connected directly to the post which carries the movable presser member.

Other objects and advantages will be apparent from the following detailed description of the invention and will be pointed out in the claims.

In the drawings,—

Figure 1 is a side elevation, partly in section, of a clicking machine showing one embodiment of my invention; and

Fig. 2 is a front view of the novel mechanism for operating the movable presser member.

In the illustrative machine there are disclosed a cutting bed 4 and a movable presser member 6, the latter being supported on a post 8 which is reciprocable to effect pressure-applying movements of the presser member toward the cutting bed. Pivoted at 10 in the frame 12 of the machine is a lever 14 provided with a handle 16 for controlling the movements of the presser member, depression of the handle resulting in the setting of the clutch (not shown) on the main shaft 17 to effect a single revolution of said main shaft and pressure-applying operations of the presser member. As disclosed, the lever 14 is connected to the clutch-operating lever 18 by means of the rod 20. The mechanism thus far described is practically identical with that disclosed in the patent to Arthur Bates No. 921,503, granted May 11, 1909.

2

In the illustrative embodiment of the invention, a rod 22 is fixedly attached to the lower end of the vertically reciprocable post 8 and is extended downwardly a considerable distance below the lower end of the post. Pivoted to the lower end of the post 22 is a pair of bell-crank members 24, a pin 26 providing the connection between said members and the rod, the latter being provided with an enlarged bearing portion 28 through which the pin 26 is passed. To the upper end of each bell-crank member there is pivoted, by means of a pin 30, a link 32 which in turn is pivoted at 34 to the frame 15 of the machine. The two links and the two bell-crank members just described provide a double toggle mechanism operatively connected to the main shaft of the machine to be operated thereby by means of a pitman 36 pivoted at 38 separately to each bell-crank member 24 and provided at its other end with a strap portion 40 surrounding an eccentric 42 on the main shaft 17. Since the upper link of each toggle is pivoted to 25 the frame of the machine and the other link of the said toggle is attached to the lower end of the bar 22, it is clear that straightening of the toggle will result in downward movement of the rod 22 and therefore of the post and the presser member carried thereby. In the construction shown, the presser member is operated to deliver two pressure-applying strokes on the die supported on the cutting bed, the construction preferably being such that the 30 toggle mechanism is first straightened to cause a full length pressure-applying stroke of the presser member, the toggle mechanism then moving beyond center to cause separation of the presser member and the cutting bed by lifting the presser member a short distance, which may be varied considerably but which is preferably of such an extent as to just release the pressure of the 35 presser member upon the die so that there is no possibility of lateral movement of the presser member away from the die. This movement of separation of the presser members is followed by the re-application of 40 pressure upon the die through a second and shorter stroke of the presser member as the toggle mechanism returns to straightened position after having moved beyond center. My invention contemplates that the 45 second stroke may become practically the equivalent of the first stroke in its extent and duration when the working conditions make it necessary or desirable so to construct the machine. In such a construction the toggle will be broken more or less 50 equal distances on each side of its straight position so that it is twice straightened for each single revolution of the eccentric shaft resulting from a single actuation of the 55 starting or controlling handle on the presser

member. Alternatively, the clutch mechanism of a machine of this class might be modified to obtain two rotations of the eccentric shaft for each actuation of the starting handle and thus obtain the double cutting stroke. 70

In the construction shown, there is preferably provided a brake mechanism which becomes operative to retard the rotative movement of the main shaft as the presser member is approaching its upper position of rest, the said brake mechanism consisting of the ordinary brake band 44 surrounding a brake collar 46 on said main shaft and having its ends attached adjustably to an arm 48 fixedly mounted upon the counter shaft 50, the said shaft being provided with a second arm 52 having its forward forked end 53 secured to the pin 26 which passes through the lower end of the bar or rod 22. 80 The arrangement is such that as the toggle mechanism begins to straighten, thus lowering the post 8, the arm 52 is oscillated to release the tension on the brake band 44 so that the latter is slackened during the rotation 90 of the main shaft, then, as the toggle mechanism is broken, the same arm 52 is rocked so that at the termination of the upward movement of the presser member, the brake is applied to prevent further rotation of the 95 shaft, whereby the presser member is maintained at the upper limit of its movement. 100

In operating with the machine just described, the operative places a sheet or sheets of material, such, for instance, as fabric, leather or leatherboard, upon the cutting bed 4 and places the die 55 in selected position upon the material. During the positioning of the die, the presser member 6 is disposed at one side of the cutting bed in 105 order to permit of freedom of movement of the die and access of proper light to the work. The operative swings the presser member over the die and causes pressure-applying movements of the presser member 110 by depressing the handle 16 on lever 14. In the same cycle of operations, the presser 115 sionally happens that the first stroke on the material in order to insure clean cutting of blanks from the material. Since it occasionally happens that the first stroke on the die does not accomplish the separation of the blank from the material, a second stroke of the presser member may be depended upon to effect this result. The organized 120 machine has the advantage of producing two strokes of the presser member upon one depression of the controlling or starting lever for the machine, whereas in the ordinary or commercial form of the clicking machine, the operative is required to depress the starting lever once for each pressure-applying movement of the presser member. While the construction may be such that the second 125 pressure-applying movement of the presser 130

member may be practically equivalent to the first, it is preferable that the second stroke be very much shorter in order that no displacement of the presser member relatively 5 to the die may take place.

Having described my invention, what I claim as new and desire to secure by Letters Patent of the United States is:

1. A press constructed to stop automatically 10 at the end of each cycle and having in combination presser members relatively movable toward and from each other in pressure-applying operations on work located between the presser members, and means 15 for causing a plurality of pressure-applying operations in each cycle of the machine.

2. A press having presser members relatively movable toward and from each other in pressure-applying operations, on work 20 located between the presser members, and means comprising manually operable controlling means for causing in each cycle of the machine a plurality of pressure-applying 25 movements to insure the desired effect on the work upon a single actuation of the controlling means.

3. In a machine of the class described, presser members relatively movable toward and from each other in pressure-applying 30 operations, and means for causing a pressure-applying operation, a movement of separation of less extent than the movement of applying pressure, and then a second movement for the application of pressure 35 all in the same cycle of operations of the machine.

4. In a machine of the class described, presser members relatively movable toward and from each other in pressure-applying 40 operations, and means for causing a pressure-applying operation and a movement of separation of less extent than the movement of applying pressure and then an automatic re-application of pressure in the same cycle 45 of operations of the machine.

5. In a machine for operating on work by means of a die, a cutting bed, a presser member movable toward and from said cutting bed in pressure-applying operations to 50 force the die into the work, and means comprising a toggle mechanism for causing the application of pressure to a die on the cutting bed, the relief of said pressure and the re-application of pressure upon the die all 55 in the same cycle of operations of the machine, to insure that the die will be forced completely through the work in each cycle of the machine.

6. In a machine of the class described, 60 a cutting bed, a presser member movable toward and from said cutting bed in pressure-applying operations, and means comprising manually operable controlling means for causing upon actuation of the controlling 65 means a relatively long movement

of approach of the presser member with respect to the cutting bed, then a relatively short movement of retraction and approach, and finally a relatively long movement of separation from the cutting bed, all in the 70 same cycle of operations of the machine.

7. A press constructed to stop automatically at the end of each cycle and having in combination a cutting bed, a presser member movable toward and from said cutting bed 75 in pressure-applying operations, and means comprising a toggle mechanism operatively connected to the presser member for causing the presser member to approach the cutting bed in the pressure-applying operation, the said toggle mechanism being movable beyond center to cause retraction of the presser member and returnable to central position to cause the re-application of pressure by the presser member. 80

8. In a machine of the class described, a cutting bed, a presser member movable toward and from said cutting bed in pressure-applying operations, and means comprising a toggle mechanism operatively 90 connected to the presser member for causing the presser member to approach the cutting bed in a pressure-applying operation on a die, the said toggle mechanism being movable beyond center a relatively 95 short distance to cause retraction of the presser member to relieve pressure upon the die, and returnable to central position to cause the re-application of pressure on the die by the presser member. 100

9. In a machine of the class described, a cutting bed, a presser member oscillatable over the cutting bed and also movable toward and from the cutting bed in pressure-applying operations, a post carrying 105 said presser member, and means comprising a toggle mechanism directly connected to said post for causing the pressure-applying operations of the presser member by the operation of the toggle mechanism. 110

10. In a machine of the class described, a cutting bed, a presser member oscillatable over the cutting bed and also movable toward and from the cutting bed in pressure-applying operations, a post movably 115 carrying said presser member, a rod fixedly attached to and extending from said post, and means comprising a toggle mechanism attached to said rod for causing pressure-applying movements of the presser member 120 by the straightening of the toggle.

11. In a machine of the class described, a cutting bed, a presser member oscillatable over the cutting bed and also movable toward and from the cutting bed in pressure-applying operations, a post movably carrying said presser member, a rod fixedly attached to and extending from said post, and a toggle mechanism operative to move 125 the presser member by the straightening of 130

- 4
- the toggle, said toggle mechanism comprising links pivoted to portions of the frame of the machine and to the lower end of said rod.
- 5 12. In a machine for cutting blanks from sheet material by the use of freely movable dies, presser members relatively movable toward and from each other in pressure-applying operations upon a die positioned on
- 10 the sheet material to be cut, and means comprising a toggle mechanism for causing said pressure-applying operations constructed and arranged to be straightened to cause a pressure-applying movement of the movable presser member, to move beyond center to cause separation of the presser members and to return to the straight line position to cause a second pressure-applying movement, to insure that the die will be forced
- 15 completely through the material during each cycle of operations of the machine.
13. In a machine of the class described, presser members relatively movable toward one another in pressure-applying operations, a post for carrying one of said press-
- er members, a rod fixedly attached to the lower end of said post, a bell-crank pivoted to the lower end of said rod, a link pivoted to the upper end of said bell-crank and to the frame of the machine, thus forming a 30 toggle mechanism, and means operatively connected to the bell-crank to cause straightening of the toggle mechanism and a pressure-applying movement of the movable presser member.
- 35 14. In a machine of the class described, a cutting bed, a presser member movable toward and from the cutting bed in pressure-applying operations, a post carrying said presser member, a main shaft, means 40 comprising a toggle mechanism operated from said shaft and directly connected to said post for causing the pressure-applying operations of the presser member, and brake mechanism for said shaft directly operated 45 from said toggle mechanism.

In testimony whereof I have signed my name to this specification.

ARTHUR BATES.

Certificate of Correction.

It is hereby certified that in Letters Patent No. 1,436,691, granted November 28, 1922, upon the application of Arthur Bates, of Leicester, England, for an improvement in "Cutting Machines," an error appears in the printed specification requiring correction as follows: Page 2, strike out present line 113 and insert instead the words *member applies two strokes to the die on the*; and that the said Letters Patent should be read with this correction therein that the same may conform to the record of the case in the Patent Office.

Signed and sealed this 16th day of January, A. D., 1923.

[SEAL]

KARL FENNING,

Acting Commissioner of Patents.
